DESIGN FOR A GAME BOARD

William Grant Williams, Anaheim, Calif.

Application September 5, 1942, Serial No. 108,145

Term of patent 3½ years

To all whom it may concern:

Be it known that I, William Grant Williams, a citizen of the United States, residing at Anaheim, in the county of Orange and State of California, have invented a new, original, and ornamental Design for a Game Board, of which the following is a specification, reference being had to the accompanying drawing, forming part thereof.

The figure is a plan view of a game board, showing my new design.

The game board is of conventional thickness.

I claim:

The ornamental design for a game board, as shown and described.

WILLIAM GRANT WILLIAMS.
